(57) **CLAIM**

The ornamental design for a monocular smart glasses, as shown and described.

DESCRIPTION

FIG. 1 is a top, front, and left side perspective view a monocular smart glasses showing our new design.

FIG. 2 is a top, back, and right side perspective view thereof.

FIG. 3 is a top plan view thereof.

FIG. 4 is a bottom plan view thereof.

FIG. 5 is a front elevational view thereof.

FIG. 6 is a back elevational view thereof.

FIG. 7 is a left side elevational view thereof.

FIG. 8 is a right side elevational view thereof.

FIG. 9 is a top, front, and left side perspective view of the monocular smart glasses showing an alternate position with an eyepiece in a different angular position with respect to a temple piece; and,

FIG. 10 is a bottom plan view of the monocular smart glasses in the alternate position.

The text appearing in FIGS. 1, 7, and 9 forms no part of the claimed design.

The broken lines of FIGS. 1–10 illustrate portions of the monocular smart glasses that form no part of the claimed design.

1 Claim, 6 Drawing Sheets
